(57) **CLAIM**

The ornamental design for a pair of shoe inserts, as shown and described.

DESCRIPTION

FIG. 1 is a perspective view of a pair of shoe inserts, showing the top, the rear, and a side of our new design; FIG. 2 is a perspective view of the pair of shoe inserts of FIG. 1, showing the bottom, front, and opposite side; FIG. 3 is an elevational view of the front of the pair of shoe inserts;

FIG. 4 is an elevational view of the back of the pair of shoe inserts;

FIG. 5 is an elevational view of the right side of the left shoe insert or the left side of the right shoe insert;

FIG. 6 is an elevational view of the left side of the left shoe insert or the right side of the right shoe insert;

FIG. 7 is a plan view of the top of the pair of shoe inserts; and,

FIG. 8 is a plan view of the bottom of the pair of shoe inserts.
